CONSTANT TENSION WINDER

Howard P. Hart, Waterbury, Conn., assignor to
The Platt Bros. & Co., Waterbury, Conn., a
corporation of Connecticut

Application February 7, 1935, Serial No. 5,457

3 Claims. (Cl. 242—75)

This invention relates to an apparatus for winding material in strip or wire form onto a drum or similar receiver, and particularly to a device of this type which is to be used under such conditions that the material to be wound on the drum is delivered thereto at a predetermined speed.

When material in strip form or wire form is being wound on a drum, reel, spool or other rotary receiver and such material is being delivered to the receiver at a predetermined speed, the increase in diameter of the wound mass on the receiver tends to cause the material to be wound on the drum faster than it is being delivered thereto with the result that as the diameter of the wound mass increases the material being delivered to the drum or receiver will be subjected to an increased tension or pulling strain.

It is one of the objects of my present invention to provide a novel means for controlling the speed of rotation of the drum or receiver by which said speed of rotation is decelerated as the diameter of the wound mass increases so as to maintain a substantially constant tension on the material being delivered to the receiver.

In accordance with the invention the means for rotating the drum or receiver includes a variable speed transmission which has a power shaft, a transmission shaft, and a variable speed driving connection between said shafts, and means controlled by the tension of the material being delivered to the drum or receiver for adjusting this variable speed driving connection so as to maintain a speed of rotation in the drum which will provide at all times the desired tension on the material being delivered to the drum.

In order to give an understanding of the invention I have illustrated in the drawings a selected embodiment thereof of which will now be described, after which the novel features will be pointed out in the appended claims.

Fig. 1 is a side view of a device embodying my invention;

Fig. 2 is a top plan view of the pivoted support for the winding drum;

Fig. 3 is an end view looking toward the right in Fig. 2.

Fig. 4 is a diagrammatic view.

In the drawings 1 indicates the material which is to be wound on the drum or receiver and which may be in either strip form or wire form, and 2 is a rotary receiver on which the material 1 is wound. This rotary receiver may be in the form of a reel or a spool or a drum or have any other desirable construction. It is shown as mounted

on a shaft 3 which is positively driven, the rotation of the shaft winding the strip material 1 thereon in the form of a coil as is usual in devices of this type. As stated above the device of this invention has been especially designed for winding on a receiver material in strip form or in wire form which is being delivered from some machine or apparatus at a predetermined speed. As illustrating this condition I have shown diagrammatically in Fig. 4 a pair of feed rolls 4 by which the strip material 1 is fed forward and which may form part of some machine or apparatus by which the strip 1 is subjected to some desired treatment, said strip material or wire 1 being delivered from the feed rolls 4 to the winding drum 2.

The winding drum 2 is driven by a variable speed transmission device of some suitable type and I have provided means responsive to a change in the tension to which the material 1 is subjected by the winding operation to adjust the variable speed transmission device and thereby effect a change in the speed of rotation of the shaft of the drum 2.

The shaft 3 for the drum or receiver 2 is shown as journaled in suitable bearings 5 carried by an auxiliary frame which is movably mounted on the upper end of a main supporting frame 7, the construction being such that any increase in tension to which the material 1 is subjected by the winding operation will cause the auxiliary frame 6 to move relative to the main frame 7. In an illustrated embodiment of the invention the auxiliary frame is shown at 6 and it is pivotally mounted on the main frame 7, this pivotal mounting being through the medium of a pivot shaft 8 extending through the side pieces of the frame 6 and through the upstanding portions 9 of the main frame 7.

The variable speed transmission for rotating the shaft 3 is indicated at 10 and it is mounted on the main frame 7. This variable speed transmission 10 may have any suitable construction, that herein shown being a variable speed transmission known to the trade as a "Reeves" variable speed transmission. It comprises a power shaft 11 to which power is applied and which is driven at a uniform speed and a transmission shaft 12 connected to the power shaft 11 with the variable speed transmission in the form of two expandible pulleys 13 and 14, one mounted on the power shaft 11 and the other on the transmission shaft 12, and a belt 15 connecting said pulleys. The pulleys 13, 14 are so constructed that when the two parts of one pulley

move together to enlarge the effective driving circumference of said pulley, the two parts of the other pulley will be separated, thereby reducing the effective driving circumference. This adjustment of the pulleys is effected by the two levers 16, 17 which are pivotally mounted at 18 and which are so connected that when the upper ends of the levers are moved toward each other to increase the effective driving surface of the pulley 14 the lower ends of the levers will be separated, thereby reducing the effective driving circumference of the pulley 13.

This form of variable speed transmission is one which is more or less commonly used and needs no further description herein.

The power shaft 11 may be driven in any appropriate way and I have herein shown for this purpose a belt pulley 19 thereon. Any suitable driving connection between the transmission shaft 12 and the drum shaft 3 may be employed. I have shown herein a belt drive which comprises a driving pulley 20 on the transmission shaft 12 which is connected by a belt 21 to a pulley 22 on an intermediate shaft 23 that is mounted in bearings carried by the frame 7. The shaft 23 has a belt pulley 24 thereon which is connected by a belt 25 with a belt pulley 26 on the shaft 3.

I have stated above that the auxiliary frame 6 on which the shaft 3 is journaled is pivotally connected to the main frame 7 and preferably the construction will be such that the pivotal axis of the frame 6 will be either below or above the shaft 3. In the construction shown the pivotal shaft 8 is situated below the shaft 3.

Assuming that the variable speed transmission is set so that the surface speed of the drum 2 is substantially the same as that at which the material 1 is being delivered by the feed rolls 4, it will be understood that as the material 1 accumulates on the drum the correspondingly increased surface speed of the drum will develop an increased tension or pulling strain on the material 1 between the delivery rolls 4 and the drum, and because of the pivotal mounting of the frame 6 this increased tension will tend to swing the frame clockwise about the pivot 8 in Fig. 1. This swinging or turning movement of the frame 6 is utilized to adjust automatically the variable speed transmission 10 so as to cause a reduction of the speed of rotation of the transmission shaft 12 and consequently of the shaft 3 to a point at which the surface speed of the mass or coil on the drum 2 is the same as that at which the material 1 is being delivered from the delivery rolls 4. To accomplish this I have provided a variable speed transmission control in the form of a lever 27 pivoted to the variable speed transmission frame at 28, said control lever being connected to the upper end of the lever 16 by a link 29 and to the upper end of the lever 17 by a link 30. These links 29 and 30 are pivotally connected to the control lever 27 at points 31 and 32 respectively located on opposite sides of the pivot 28 so that as the control lever 27 is turned about its pivot the upper ends of the two levers 16, 17 will be separated or moved toward each other depending upon the direction in which the control lever 27 is turned. This control lever 27 is connected to the frame 6 so that a swinging or turning movement of the frame 6 caused by the development of an increased tension or pulling strain in the material 1 will turn the control lever 27 and thus adjust the variable speed transmission. The frame 6 is shown as having an extension 33 which is connected to the control lever 27

through the medium of a link connection 34, the latter having a forked lower end 35 which is pivotally connected to the control lever at 36 and having a ball and socket connection 37 with the extension 33.

The extension 33 is shown as provided with a weight 38 which is adjustable on the extension and hence before the winding begins the frame 6 will assume the dotted line position Fig. 1. The variable speed transmission will be initially adjusted so that the surface speed of the empty spool will be substantially the same as that at which the material 1 is being delivered from the delivery rolls 4, and when the winding operation begins the parts will be adjusted so that there is a slight tension on the length of material 1 between the delivery rolls 4 and the drum or spool 2, the variable speed transmission being adjusted so as to maintain this slight tension. As the winding proceeds and the coil of material on the receiver 2 increases in diameter, there will be an increasing tension applied to the material 1 between the delivery rolls and the drum because of the fact that the material is being delivered at a predetermined speed from the delivery rolls. This increased tension will swing the frame 6 about its pivot 8 from the dotted line position toward the full line position, and this swinging movement of the frame 6 operates through the connection 34 to adjust the control lever 27, and thereby adjust the variable speed transmission, thereby to reduce the speed of the transmission shaft 12 and consequently reduce the speed of the drum shaft 3. By means of this construction the variable speed transmission will be automatically adjusted as the diameter of the coil on the drum 2 increases so as to maintain a surface speed of the drum substantially the same as the speed with which the material is delivered from the delivery rolls and hence to maintain a substantially constant tension on the material between the delivery rolls and the drum or receiver 2.

The amount of this constant tension can be varied by adjusting the counter-weight 38, an adjustment of the weight toward the left Fig. 1 resulting in maintaining an increased constant tension on the material 1, and an adjustment to the right resulting in maintaining a decreased constant tension on said material 1.

While I have shown an auxiliary frame 6 which is capable of movement relative to the main frame 7 by virtue of its pivotal mounting on said main frame, yet this particular way of providing for the movement of the auxiliary frame relative to the main frame is not essential to the invention and other constructions may be used which will produce the results herein described. My improvements, therefore, provide a device including a drum on which the material is wound, means to rotate the drum and means responsive to a change in the tension to which the material being delivered to the drum is subjected by the winding operation to vary the speed of rotation of the drum. Furthermore, such variation in speed of rotation of the drum is provided for in such a way as to maintain a substantially constant tension on the material being delivered to the drum.

I claim:

1. An apparatus for winding material in strip or wire form which is being delivered at a predetermined rate, said apparatus comprising a main frame, an auxiliary frame movably mounted on the main frame, a drum journaled on the auxiliary frame on which the material is wound, means to rotate the drum including a variable speed

transmission mounted on the main frame and having a power shaft, a transmission shaft and a variable speed driving connection between said shafts and a mechanical connection between said auxiliary frame and said variable speed driving connection by which movement of the auxiliary frame induced by the change of tension to which said material is subjected actuates said variable speed driving connection to produce a compensating change in the speed of rotation of the drum.

2. An apparatus for winding material in strip or wire form which is being delivered at a predetermined rate, said apparatus comprising a supporting frame, a winding drum on which the material is wound, an auxiliary frame carrying said drum movably mounted on the supporting frame, said auxiliary frame being adapted for movement on the supporting frame under tension of the material, means for rotating the drum including a power shaft, a transmission shaft and a variable speed driving connection between said power shaft and transmission shaft, a control lever for adjusting said variable speed driving

connection and means for connecting said lever to said auxiliary frame whereby movement of the auxiliary frame induced by an increased tension on the material effects an adjustment of the variable speed driving connection to decrease the speed of rotation of the drum.

3. An apparatus for winding material in strip or wire form which is being delivered at a predetermined rate, said apparatus comprising a main frame, a rotatable drum on which the material is wound, an auxiliary frame on which the drum is journaled and which is movably mounted on the main frame and is adapted to be moved thereon by increased tension in the material, means for rotating the winding drum including a power shaft, a transmission shaft and a variable speed driving connection between said shafts and a connection between said auxiliary frame and the variable speed driving connection by which movement of the auxiliary frame induced by an increased tension in the material being wound adjusts said variable speed driving connection to reduce the speed of rotation of the drum.
